UNITED STATES PATENT OFFICE.

EDWIN W. BAILEY, OF LAWLEY, ALABAMA.

BACKBAND HOOK.

Application filed December 14, 1921. Serial No. 522,254.

To all whom it may concern:

Be it known that I, EDWIN W. BAILEY, a citizen of the United States, and a resident of Lawley, in the county of Bibb and State of Alabama, have invented a new and Improved Backband Hook, of which the following is a full, clear, and exact description.

This invention relates to improvements in hooks for the back bands of draft animals, the principal object of the invention being to provide a hook of this character, which will serve to firmly support the trace chains and prevent the same from slipping in either direction.

A further object is to provide a hook so constructed that a trace chain may be readily attached thereto, and a hook which will be simple and practical in construction, strong, durable and efficient in use, and comparatively inexpensive to manufacture.

With these and other objects in view, the invention consists in certain novel features of construction and combinations and arrangements of parts as will be more fully herein-after described and pointed out in the claims.

In the accompanying drawing:

Figure 1 is a fragmentary view of one end of the back band showing my improved hook attached thereto;

Figure 2 is an edge view of Figure 1; and

Figure 3 is an edge view of Figure 1, showing the manner of operating the hook to permit the attachment or removal of the trace chain therefrom.

Referring in detail to the drawings, I have used the reference numeral 1 to designate a back band for draft animals. A metal plate 2 is bent transversely and has its ends straddling the end of the back band and secured thereto by suitable securing devices, such as the rivets 3. The intermediate portion of this metal plate or sheet 2 is bent to provide a sleeve 4 receiving a pin 5, the intermediate portion of said sheet being recessed, as indicated at 6, to expose the pin.

A plate 7 includes at its upper end, a pair of apertured ears or extensions 8 pivotally mounted upon the pin 5 and at its lower end is provided with a pair of integral upwardly extending hooks 9, said hooks being spaced apart to accommodate an arm 10 pivotally mounted upon the pin 5 between the ears 8. The arm 10 carries a finger 11 which engages with the plate 7 to limit the pivotal movement of the arm in one direc-

tion. This finger is movable between the hooks 9 and when the same engages the plate, the arm 10 is in parallelism and alignment with the hooks 9.

The numeral 12 is used to designate a guard flap riveted to the under side of the end of the back band 1 by rivets 13 and if desired, the rivets 3 may also be utilized in securing this flap firmly to the back band. The flap extends beyond the end of the back band and serves to guard the side of a draft animal from contact with the plate 7, so that the plate will not cause chafing. It will be noted that the arm 10 extends below the hooks 9 providing a finger receiving extension 14 to facilitate the lifting or operating of the arm.

The manner of operation of the hook is as follows: It will of course be understood that one of these hooks is provided at each end of the back band for the purpose of receiving the trace chains, designated by the reference numeral 15. In attaching the chains, the flexibility of the guard flap 12 permits the raising of the arm 10, as seen most clearly in Figure 3. The chain may then be passed under the arm and one link of the same inserted between the plate 7 and the hooks 9. As the arm 10 is restored to its normal position, the finger 11 will pass through the link of the chain and engage the plate 7 so that the link is positively held against slipping in either direction. It is of course necessary to manually flap the flap 12 when attaching or removing the trace chain.

Although I have illustrated one of the preferred embodiments of my invention, it will be apparent that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

I claim:

1. A back band hook, including a pivoted plate, hooks integral with the plate, a pivoted arm movable between the hooks, and means carried by said arm engageable with the plate to limit the pivotal movement of the arm and with a link of a chain to hold said chain against movement.

2. In a back band hook, a plate having

knuckles, a second plate having a pair of ears, a pin passed through said knuckles and ears, hooks integral with the second plate, an arm pivoted on the pin between the ears, the free end of said arm being movable between said hooks, and means on the arm intermediate of its ends cooperating with said hooks to hold the chain against movement.

3. In a back band hook, a pivoted plate, 10 hooks integral with the plate, the free ends of said hooks extending in parallelism with the plate and being spaced from the plate and each other, a pivoted arm movable between the hooks, and a finger carried by 15 said arm and adapted to pass through a link of a chain and engage the plate.

EDWIN W. BAILEY.
